UNITED STATES PATENT OFFICE.

STEPHEN H. BELLOWS, OF ATHOL, MASSACHUSETTS.

COMBINATION-SQUARE.

SPECIFICATION forming part of Letters Patent No. 249,821, dated November 22, 1881.

Application filed February 4, 1881. (No model.)

To all whom it may concern:

Be it known that I, STEPHEN H. BELLOWS, of Athol, in the county of Worcester and State of Massachusetts, have invented a certain 5 new and useful Improvement in Combination-Squares, of which the following is a description, reference being had to the accompanying drawings, wherein—

Figure 1 is a side view of a combination-square embodying my said improvement. Fig. 10 2 is a view of same in vertical cross-section on plane $x x$, Fig. 1. Fig. 3 is a side view of a portion of the instrument, modified by addition of a spirit-level.

15 The letter A denotes a metallic block, base, or frame bearing a mortise, b, for the reception of the graduated sliding blade o, one side, b', of which mortise is a seat for such blade, which, when the blade rests against it, maintains the 20 blade in proper relation to all the arms, hereinafter described, which are fixed to the base A.

The letter c denotes a right-angular arm fixed to the base A, by means of which the instrument is usable as a common try-square. d 25 denotes an arm, by which bevel or miter lines can be made, and therefore called a "bevel-arm." e and e' denote two arms fixed to the base A, which can be used to find the center of shafts and the like, and therefore called "centering- 30 arms."

The base A is composed of two separate parts or base-sections, a and a', which are riveted together, as indicated in dotted lines. It will be observed that the seat for the blade b' 35 is a part of that face of base-section a which meets a corresponding face of section a'. Said face, which is the seat b', can be readily and cheaply made true, when exposed for work thereon, before the two base-sections are fastened together, and the mortise b can be readily and cheaply made in base-section a', when said face thereof is exposed, before the two sections are fastened together. To make mortise b and seat b' by broaching or the like through 40 a solid piece of suitable metal would be difficult and expensive. The blade is fastened at any desired point in base A by means of the set-screw f, having a shoe, g, intermediate between

it and the blade, also the compression helical spring h, acting from the screw to the shoe. 50 The inner end of the shoe g is frusto-conical, and it lies in a round socket, i, which will not permit it to project so far into the path of the blade (this when the blade is out of the base) that the end of the blade (in replacing it) can 55 strike against the vertical side of the shoe, but (in thus replacing the blade) it will strike the conical face of the shoe, and thus force it back so that the blade can pass. The pressure of the spring h, when the screw is slightly loosened, keeps the blade against its seat, so that it does not drop out of the base accidentally, nor permit dirt to get between the blade and its seat.

It will be observed that this organization of 65 parts attains the desideratum of a screw, which, bearing on the edge of the blade, pushes the blade to its seat rather than pulls it, though a clamp-bolt pulling the blade to its seat can be used in the place of the set-screw and be 70 an equivalent therefor, except as to the special advantage just named.

I claim as my improvement—

1. The base A, bearing the right-angular arm c, bevel-arm d, centering-arms e e, and 75 blade-seat b', common to all the arms, in combination with the sliding blade and the set-screw, all substantially as described, and for the purpose set forth.

2. The base-sections a, bearing the arms d 80 e and blade-seat b', joined to the base-section a', bearing the arms e e and mortise b, and combined with the blade and set-screw, all substantially as described, and for the purpose set forth.

3. In combination, the mortised base A, the sliding blade o, the beveled shoe g, and the set-screw, all substantially as described, and for the purpose set forth.

In witness whereof I hereto set my hand this 90 31st day of January, A. D. 1881.

STEPHEN H. BELLOWS.
